UNITED STATES PATENT OFFICE.

LOUIS R. MENDELSON, OF CLEVELAND, OHIO.

BURNER.

Application filed April 21, 1924. Serial No. 707,916.

To all whom it may concern:

Be it known that I, LOUIS R. MENDELSON, a citizen of the United States, residing at Cleveland, in the county of Cuyahoga and 5 State of Ohio, have invented certain new and useful Improvements in Burners, of which the following is a specification.

This invention relates to improvements in gas burners.

10 The object of the present invention is to provide an improved burner which may be easily and inexpensively formed by a simple casting operation; in which there is no central flat top surface of such extent that dirt 15 and the like might collect thereon and close adjacent jet orifices; in which the mixture of gas and air is distributed substantially uniformly throughout the burner chambers, from which it passes through properly ar- 20 ranged jet orifices to produce a substantially uniform flame over the top of the burner; and which burner is so formed that sufficient air is directed to the space above the central portion of the burner to ensure perfect combustion and maximum heating effects.

Further objects of the invention are in part obvious and in part will appear more in detail hereinafter.

25 In the drawing, Fig. 1 is a plan view of my improved burner arranged within the casing of a water heater; Fig. 2 is a bottom plan view of the burner with the central depending tubular portion broken away to more clearly illustrate the chamber passages; and Fig. 3 is a vertical sectional view on the line 3—3, Fig. 1.

Referring to the drawing, the burner therein illustrated comprises in general outline a substantially flat circular top, a relatively narrow annular side wall, and a downwardly and inwardly inclined bottom terminating in a centrally disposed depending tubular connecting portion 10. More specifically, the burner comprises an enlarged central distributing portion 11 above the tubular portion 10, a marginal or circumferential portion 12 and radially extending spaced connecting portions 13, three such connecting portions being here shown, the burner being formed in one or two pieces by a simple casting operation. While the top wall of the burner may be provided with any suitable number and arrangement of jet orifices or gas tips, the marginal portion 12 is here provided with two concentric series of orifices 14 and the radial connecting por-

tions 13 are each provided with two radially extending rows of orifices. The gas flame is, therefore, distributed over substantially the entire burner top.

60 As clearly indicated in the drawings, the top wall of the central distributing portion 11 is formed with a plurality of elongated, substantially V-shaped depressions 15 arranged between adjacent radial connecting portions 13 and extending downwardly and outwardly from substantially the center of the top wall of the central distributing portion. While three such depressions are here shown, it will be understood that if the number of radial connecting portions 13 is varied, such as by being increased to four, the number of depressions 15 will be correspondingly varied.

65 These inclined depressions 15 serve three purposes. First, they avoid the formation of the upper wall of the central distributing portion as a flattened surface of sufficient extent as to collect dirt and the like thereon which might close adjacent jet orifices. Second, the air travelling upwardly through the three circumferentially spaced, elongated openings 16 between the radial connecting portions 13 passes along these depressions to the space above the central portion of the burner so that sufficient air is provided for a proper mixture of gas and air, thereby ensuring maximum heating effects. In order to ensure the travel of the air upwardly 80 along these depressions, the marginal portion 12 is provided with three projections 18 extending inwardly into the air openings 16 opposite the depressions 15. These projections have inclined bottom walls 19 which 85

90 direct or deflect the air toward the depressions 15. Preferably, these projections are each provided in their upper wall with one or more jet orifices 14. The third purpose of the depressions 15 is to direct the mixture of gas and air entering the chamber 20 of the central distributing portion 11 into the passages 21 of the radial connecting portions 13 and thence into the annular passage 22 of the marginal or circumferential portion 12. As clearly indicated in Fig. 2, the 95 gas and air mixture entering the central chamber 20 will be deflected by the inner angular surfaces 23 of the depression wall portions into the radial passages 21. The 100 mixture of gas and air is therefore substantially uniformly distributed in the burner chambers and a substantially uni- 105 110

form flame produced over the upper burner surface.

In the present embodiment, the burner is illustrated as arranged within the cylindrical casing 30 of a water heater. For this purpose, the marginal portion 12 of the burner is provided with a plurality of integrally formed, outwardly extending supporting lugs, three being here shown. The two diametrically opposed burner lugs 31 are adapted to rest upon the inwardly extending lugs 32 of the heater casing, while the third burner lug 33 between lugs 31 is adapted to project through a suitable aperture in the heater casing, and receive outside of said casing a cotter pin 34 or other suitable securing means. The tubular connecting portion 10 of the burner is mounted upon the upper tubular end 35 of the usual primary gas and air mixing casing. Suitably arranged within the casing and above the burner is a coil 36 through which circulates the water to be heated by the burner.

What I claim is:

1. A gas burner, comprising a central portion, a marginal portion, and radially extending connecting portions, the upper wall of said central portion being provided with elongated depressions extending downwardly and outwardly from substantially the center of the upper surface of said central portion.

2. A gas burner, comprising a central portion, a marginal portion, and radially extending, spaced connecting portions, the upper wall of said central portion being provided with elongated depressions arranged between adjacent radial connecting portions and extending downwardly and outwardly from substantially the center of the upper wall of said central portion.

3. A gas burner formed in one piece and comprising a central portion, a marginal portion, and radially extending, spaced connecting portions, the upper wall of said central portion being provided with elongated depressions arranged between adjacent radial connecting portions and extending downwardly and outwardly from sub-

stantially the center of the upper wall of 50 said central portion.

4. A gas burner, comprising a central portion, a marginal portion, and radially extending, spaced connecting portions, the upper wall of said central portion being provided with substantially V-shaped depressions arranged between adjacent radial connecting portions and extending downwardly and outwardly from substantially 55 the center of the upper wall of said central portion.

5. A gas burner, comprising a central portion, a marginal portion, and radially extending, spaced connecting portions, the upper wall of said central portion being provided with elongated depressions arranged between adjacent radial connecting portions and extending downwardly and outwardly from substantially 60 the center of the upper wall of said central portion, said marginal portion being provided with inwardly extending projections opposite said depressions for guiding the air passing through the spaces between the radial connecting portion 65 upwardly along said depressions.

6. A gas burner, comprising a central chamber for receiving a mixture of gas and air, an annular marginal chamber, and radially extending chambers connecting the central and marginal chambers, and means for directing the mixture of gas and air delivered into said central chamber into said radial chambers and thence into said marginal chamber.

7. A gas burner, comprising a central 85 chamber for receiving a mixture of gas and air, an annular marginal chamber, and radially extending chambers connecting the central and marginal chambers, the wall of 90 said central receiving chamber being depressed into said chamber at one point at least for directing the mixture of gas and air into one or more of said radial chambers.

In testimony whereof I hereby affix my 95 signature.

LOUIS R. MENDELSON.
